METHOD AND MEANS FOR PURIFYING
LUBRICATING OIL

Southwick W. Briggs, Washington, D. C.

Application January 2, 1935, Serial No. 163

2 Claims. (Cl. 210—134)

This invention relates generally to the purification of lubricating oil during use thereof in an engine, and more particularly in the lubricating system of an internal combustion engine, especially an automobile engine.

The principal objects of the invention are the provision of a new and useful method of and means for purifying lubricating oil under such conditions.

10 In the use of internal combustion engines on automobiles it is common practice to circulate some of the oil from the crank case under pressure through filtering material and back to the crank case. While the quantity of oil thus circulated through the filtering medium is relatively small, yet the continued circulation of oil while the engine is running soon passes the entire volume of oil in the lubricating system through the filtering medium and does so repeatedly. Cotton 15 fiber in the form of waste has been suggested as a filtering material. Fuller's earth, when employed in the manner set forth in my Patent 1,860,229, granted May 24, 1932, has been successfully and extensively used.

25 According to the method and means of the present invention, improved results are realized by circulating the oil under pressure through both a suitable fibrous material such as cotton waste, and a suitable adsorbent material such as fuller's earth, among the important advantages being that each material removes some of the impurities, especially those which it is best adapted to remove, and that removal of some of the impurities by the fibrous material makes it 30 possible for the fuller's earth to act more effectively in removing other impurities which are not removed or removable by the fibrous material.

The invention and the aforesaid and other objects and advantages realized thereby will be 40 fully understood by reference to the embodiments thereof shown in the accompanying drawings and to the following detailed description in connection with said drawings, wherein—

45 Figure 1 is a vertical sectional view, with parts shown in elevation, of one embodiment of the invention;

Fig. 2 is a view in perspective and section of parts at the upper end of the filter of Fig. 1 shown separated one above another;

50 Fig. 3 is a view in elevation of a piece of flexible tubing;

Fig. 4 is a perspective view of a roll of fibrous filtering material;

55 Fig. 5 is a vertical sectional view, with parts

in section, of another embodiment of the invention;

Fig. 6 is a detail perspective view of one of the straps shown in Fig. 5 for securing the filter in place on an automobile; and

Fig. 7 is a detail view, partly in section, showing the use of a check-valve in the oil feed line of Fig. 1.

Referring to Figs. 1 to 4—10 is an outer casing or jacket of cylindrical form closed at its lower end by bottom wall 11 and having an outwardly projecting annular flange 12 around its open upper end, the upper surface of said flange constituting a seat against which other parts presently described are secured to form a liquid tight joint 10 at the top of the casing. The casing 10, its bottom 11 and the flange 12, are preferably integrally formed from a single piece of sheet steel by stamping or other well known method. Casing 10 may be supported in any suitable manner in 15 convenient relationship to an engine with which it is to be associated. For example, it may be mounted on the engine itself, or, as shown in Fig. 1, it may be provided with bracket 13 and the latter secured to the dash 14 of an automobile by 20 bolts 15, 15, engaging nuts 16, 16, the latter being preferably spot-welded to the bracket 13.

11 is a pipe (known as the "oil return line") for conducting filtered oil from the filter back to the engine. At its upper end pipe 11 is secured in a pipe joint 18 the upper end of which is screw-threaded upwardly through an opening 19 in flange 12 of the casing and made flush with the upper surface of said flange (Figs. 1 and 2).

An annular gasket or packing 20, of the same 35 external diameter as flange 12, fits against the upper surface of said flange and has therethrough an opening 21 registering with the opening 19 in the flange and also with the upper end 40 of the passage through pipe joint 18. An annular disk 22 of sheet steel, of the same external diameter as flange 12 and gasket 20, fits against the upper face of the latter and has an opening 23 therethrough registering with opening 21 through said gasket. The central space in disk 45 22 is covered by a screen 24 positioned against the bottom surface of a circular perforated plate 25, said screen and plate being secured or clamped in place around their peripheral edges by a ring 26 of approximate S-shape in cross-section, as best shown in Fig. 2. Disk 22 with the screen 24 and perforated plate 25 together 50 constitute what is termed the "filter-head." The screen 24 is preferably of Monel metal and of fine mesh, say about #140, which is about 55

one-twelfth the size of the particles or granules of the fuller's earth mentioned hereafter. The presence of this screen is principally an emergency provision to stop any small particles of the fuller's earth or other solid matter that may become suspended in the oil before it passes through the screen to the outlet from the filter.

27 is another annular gasket seated against the upper surface of disk 22 and of the same 10 outside diameter as said disk. Gasket 27 is cut away, or slotted, at 28, the outer extremity of this slot being rounded and registering with the opening 23 in disk 22. 29 is the circular cover for the casing which is of the same exterior diameter as the gasket 27 and fits against the latter and is somewhat bulged outwardly or domed at its middle. A series of bolts 30 spaced apart 15 entirely around the casing and each extending through registering openings such as 31 (in flange 12), 32 (in gasket 28), 33 (in disk 22), 34 (in gasket 27) and a correspondingly positioned opening in cover 29, securely bind all of said parts together to form a liquid-tight joint 20 between said cover plate 28 and the flange 12 of the casing, with the exception of the liquid outlet passage leading from the space immediately beneath the cover radially through the slot 28 of gasket 27 and thence downward 25 through openings 23 and 21 and through fitting 18 to return pipe 17. A pipe joint 35 connects the lower end of pipe 17 to the side branch of a T-coupling 36, the upper branch of which engages the lower end of a threaded nipple 37 which passes through an opening in the center of 30 the bottom 11 of the casing. The upper end of nipple 37 is engaged by a relief valve 38 located inside of the casing and of well-known standard construction including a tubular inlet plug, a ball valve seated against the inner end of said 35 plug, a coiled spring acting at one end upon said valve, and a plug against which said spring seats at its other end.

A pipe 39, a small part only of which is shown in Fig. 1, is connected at its upper end by a pipe 45 joint 40 to the lower branch of T-coupling 36 and at its lower end by a pipe joint 41 to the interior of the crank-case of the engine through a portion of the wall of said case shown at 42. A nipple 43 threaded through an opening in another part 42' of the crank-case wall is engaged 50 at its upper end by a T-coupling 44. A pipe 45 (known as the "gauge line") is joined to the upper branch of said coupling and leads to oil gauge 46 at a suitable location. A pipe 47 (known as the "feed line" to the filter) is connected at its lower end to the side branch of T-coupling 44 by a pipe joint 48 having there- 55 through a small passage 49, preferably a #50 drill hole, which is a hole of an approximate 60 diameter of 7/100 of an inch. At its upper end pipe 47 is connected to an elbow 50 by a pipe joint 51. A nipple 52 (similar to nipple 37) is screw-threaded at one end in an opening 65 through the side wall of casing 10 and at its other end into the elbow 50. Through the connections thus described the pipe or "feed line" 47 conducts oil under pressure from the crank case or lubricating system to the interior of outer casing 10 while the engine is running.

A drain opening through the bottom wall 11 of the casing is closed by a removable screw-threaded plug 53. A short section of flexible tubing 54 (of suitable material, such as "Du- 70 prene"), as shown in Fig. 3, may be interposed

by suitable connections in each of the pipes 47 and 39 and serve, when the filter is mounted on the dash, to absorb vibrations between the parts rigidly attached to the crank-case and filter respectively. The use of such flexible tubing is unnecessary when the filter is mounted on the engine. The pipes 17, 39, 45 and 47 are preferably $\frac{1}{8}$ inch copper tubing; and the pipe joints 18, 35, 40, 41 and 51 are preferably $\frac{1}{8}$ inch compression fittings of well known standard construction. Pipe joint 48, having a #50 drill hole, is also preferably a compression fitting.

As readily appears, removal of the bolts 30 permits removal of the cover 29 and associated parts which close the upper end of casing 10, thus giving access to the interior of said casing (for removal and replacement of the inner receptacle or "refill", or for other purpose) without disconnecting or otherwise disturbing any of the connections to the filter for pipes leading to and from the same and without disturbing the mounting of the filter on the automobile. On this point the connecting of the oil return line or pipe 17 with the opening 19 through the flange 12 by means of the pipe joint 18 is of special importance; and in respect thereto the present application is a continuation-in-part of my earlier application filed July 27, 1933, Serial No. 682,507.

Within the outer casing 10, there is an inner cylindrical removable receptacle or container 55 (such as a tin can) for the filtering material, said container being permanently closed at its top by a perforated end plate 56 and the peripheral edge of the latter and the upper edge of the cylindrical side wall of the container being formed into a tight joint by crimping or otherwise in a manner well known in the making of cans or similar sheet metal articles. The lower end of container 55 is closed by a perforated 40 telescopic cover 57, secured in place by spots of solder, such as shown at 58, spaced around said cover. The container and its contents (above to be described) are known as a "refill" or "refill cartridge". A coiled spring 59, bearing at one end against the bottom wall 11 of the outer casing and at its other end against the cover or bottom 57 of the container, presses the latter upward until its upper edge engages against the bottom surface of gasket 20, forming a tight joint 50 at 60 entirely around said edge and providing a space 61 between the perforated end plate or wall 56 of the container and the bottom side of the filter head 22 and its screen 24. Spacers 62, such as short lengths of copper tubing, are soldered to the outer surface of container 55 and thus serve to firmly position the latter concentrically within the outer casing 10 while at the same time permitting the container to be freely withdrawn endwise from said casing when the cover 29 thereof is removed.

The inner surface of the vertical cylindrical wall of container 55 is covered with an adhesive 63 (such as shellac or preferably bakelite, varnish or silicate of soda) which should be impervious to the oil to be filtered. 64 is a relatively compact body of fibrous filtering material filling the lower part of the container, bearing against the cover 57 and extending across the perforations 70 therein, and attached to the side wall by the adhesive 63. The perforations in the cover are such as to freely admit oil under pressure while at the same time preventing escape of fibrous material therethrough when the engine stops (there- 75

by discontinuing the pressure on the oil) and there is a back-wash of oil through said perforations from within the container 55.

The fibrous material 64 may be ordinary cotton waste, but when such waste is used it should be carefully and skillfully handled and packed to avoid substantial variations in density or hard and soft spots in the mass. Single thread cotton waste, which as marketed is wound in skeins or loops, has been found to be of considerable advantage over ordinary waste, both as to handling and effectiveness in filtering. The skeins are cut across and several of them wound spirally into a roll with the ends at the cuts slightly overlapping, as shown in Fig. 4, thus producing a fibrous body or mass of approximately uniform or even density which can be readily handled and put in place in the container. Forming the fibrous material into a roll increases its resistance to excessive compacting endwise, such as might obstruct the desired freedom of passage of the oil therethrough.

Highly satisfactory results have also been obtained by using as the fibrous material 64 a suitable absorbent wood pulp product, preferably crepe paper, plies or layers of which may be superposed and one or more bundles of the plies then spirally wound into rolls similar to that shown in Fig. 4.

In whatever form the fibrous material 64 is used, the securing thereof to the side wall of the container by adhesive 63 has several important advantages. For example, it resists undue compacting of the fibrous material and excessive obstruction to the flow of the oil that might result from such compacting; it resists tendency of the fuller's earth to work down the side wall of the container between the same and the fibrous material; and it permits upward movement of the central portion of the fibrous material, under upward pressure of the oil, while at the same time preventing the peripheral portion of said fibrous material from being drawn away from the side wall of the container. Thus the securing of the fibrous material to the side wall of the container prevents several conditions any one or more of which might, and probably would, interfere with the proper passage of the oil under pressure through the filtering materials and the proper functioning of the filtering means or device as a whole. Said upward movement of the fibrous material under upward pressure of the oil serves an important function in connection with the overlying fuller's earth as explained hereafter.

65 is a body of suitable adsorbent filtering or refining material, preferably fuller's earth, nearly filling the container 55 above and resting upon the body of fibrous material 64, the particles of said fuller's earth at the outer or peripheral edge of the mass 65 being embedded in the adhesive 63 in accordance with the invention of my previously mentioned patent. In the construction shown in Fig. 1 it has been found preferable to employ the fibrous material 64 and the fuller's earth 65 in about equal proportions by volume; but these proportions may be varied according to the particular filtering materials employed. In the use of two kinds of filtering material as shown, the fuller's earth 65 is preferably introduced in place in an unpacked condition, thus saving the expense of packing and also avoiding the formation of "fines" or pulverulent earth due to packing. The presence of such fines in a construction of the kind illustrated would, it is believed, conduce to channelling of the oil through the

fuller's earth and also unduly obstruct the flow of oil therethrough. Furthermore, in the construction shown, the before mentioned upward movement of the fibrous material 64, caused by upward pressure of the oil, serves to impart evenly distributed pressure to the body of fuller's earth 65, thereby tending to evenly compact the same and also take up any settlement therein such as might otherwise result from jarring or vibration occurring before or after the filter is put in service.

When fuller's earth constitutes the entire filtering body, as in my above mentioned patent, and is relied upon both to mechanically filter or strain out of the oil impurities such as particles of carbon and dirt and also to remove by adsorption impurities such as acids, resins and asphaltic matter, it is desirable to employ a grade of fuller's earth composed of relatively fine particles, such as the 30-60 proportion or mesh mentioned in said patent. But when, as in the present invention, the fibrous material 64 is mainly relied upon to remove the impurities such as carbon and dirt, and the fuller's earth 65 is mainly relied upon to remove the acids, etc., it is possible and preferable to employ fuller's earth composed of larger particles, say approximating about 15-30 mesh or 8-14 mesh. While such coarser fuller's earth gives the desired adsorption filtration or refining for removing acids, resins and asphaltic matter from the oil, the larger intervening spaces or interstices between the particles thereof also provide passages through which cold or even congealed oil will circulate under pressure when the engine is started and be promptly followed by oil sufficiently heated by the engine to quickly heat the filtering materials, especially the fuller's earth, to an efficient operating temperature. Thus, the coarser fuller's earth affords not only the advantage of more free and hence speedy circulation of the oil therethrough during normal running of the engine, but also provides for better operation, especially in cold weather, upon starting the engine with the oil cold or congealed.

Above the fuller's earth 65 and filling the space between the same and the perforated end 56 of the container, there is a pad 66 of fibrous material, such as ordinary cotton waste, which is attached to the side wall of the container by the adhesive 63. This pad prevents particles of the fuller's earth from passing out of the container with the filtered oil and also prevents abrasion of the fuller's earth (with the formation of "fines") by contact with the perforated plate 56. In the absence of the pad 66, abrasion might occur in shipping and from other conditions producing relative movement between the fuller's earth and the metal plate.

The container 55 is filled by placing it, open end up, on a table or other support with its cover 57 removed. Adhesive 63 is then applied over part of the inner surface of the container. The pad 66 is then put in place and the fuller's earth 65 poured in over the pad, no special packing or compacting of the fuller's earth being required as before explained. More adhesive 63 is then applied over the rest of the inner surface of the container and the roll of fibrous material 64 is then introduced and forced into place under considerable pressure. The cover 57 is then applied and secured in place by the spots of solder 58. The filled container is slipped into the casing 10 against spring 59; the gasket 20, plate 22, gasket 27 and cover 29 are then put in position and the parts secured together by bolts 30, with the spring 59 compressed and hence under tension.

Fuller's earth is very hygroscopic. As mined it is said to contain in the neighborhood of 23% of moisture or water, this being reduced to about 17% by air drying and crushing. Its efficiency as an adsorbent filtering or refining material for the purpose of this invention increases with decrease of moisture content. Therefore it is desirable to still further reduce the moisture content and it has been found that reduction to about 10 5% can be accomplished without great difficulty by drying in an oven. To preserve this low moisture content of the fuller's earth by protecting it from absorption of moisture from the atmosphere during handling and shipment of the filled container 55 or refill, I saturate or soak the fuller's 15 earth with a suitable oil, such as the lubricating oil eventually to be circulated through the fuller's earth for filtration. It is preferable to soak the fuller's earth with the oil after the earth is put 20 in the container, but this may be done before.

The flow or circulation of oil in the construction shown in Fig. 1 is as follows: Oil from the lubricating system is forced under pressure, when the engine is running, from the crank-case at 25 42' through the restricted passage 49, pipe 47 and elbow 50 into the casing 10 which becomes filled around the container 55. Oil is then forced upward through perforated cover 57, fibrous filtering material 64, fuller's earth 65, fibrous pad 30 66, space 61, screen 24 and perforated plate 25, into the space beneath cover 29, and thence through passage 28, pipe 17, T-connection 31 and pipe 39, back to the crank-case at 42. If oil is delivered into the casing 10 faster than it can 35 circulate through the container 55 and the filtering material therein, the pressure of the oil becomes sufficient to open the relief valve 38 at the bottom of the casing 10 and permit the excessive supply of oil to be conducted (by passed) 40 through pipe 39 back to the crank-case at 42. The upward pressure of the oil entering the bottom of the container 55 imparts upward movement to the fibrous material 64, which in turn moves upward against the fuller's earth 65, as 45 before described, and presses the latter upward into a relatively compact mass against the pad of waste 66.

Oil forced under pressure from the lubricating system of the engine into the filter is charged 50 with air in substantial volume, which results from scattering and throwing of the oil about in the crank case by the rapidly rotating and vibrating parts of the engine, such as the pistons, connecting rods, crank shaft and its cranks. The 55 air with which the oil is thus charged being elastic becomes somewhat compressed in the filter and its filtering material. When the engine stops and thus discontinues the oil pressure on the intake or feed side of the filter, the compressed air 60 expands and causes a reverse or back flow or back-wash of oil which may extend back into the feed pipe 47 and be of such force as to disrupt or disarrange the filter bed, especially the body of fuller's earth. When the engine is again 65 started and the pressure of the oil thus resumed, the fibrous material 64 again moves upward against the fuller's earth 65 and thus acts to restore the proper operating condition of the filter bed.

70 It is preferred, however, to substantially avoid or limit such sudden expansion of the compressed air and the effects thereof, by providing a suitably located check valve. This is shown in Fig. 7, which is a modification of part of the construction shown in Fig. 1. The check valve is

located in the pipe joint or compression fitting 104 (corresponding to pipe joint 51 in Fig. 1) which is threaded into elbow 50, and a tubular plug 105 is screw-threaded into the end of the fitting 104. A spring 106 bears at one end against plug 105 and at its other end against a ball valve 107, tending to hold the ball seated over an opening 108. When the engine stops and thereby discontinues the pressure on the under side of ball valve 107, said valve is immediately seated 10 or closed by the reverse flow of oil and thus prevents back-wash.

The modified construction shown in Fig. 5 dispenses with an outer casing such as shown in Fig. 1, there being a single cylindrical container or receptacle 70 (such as a tin can) closed at its ends by caps 71 and 72, respectively. The peripheral edge of each cap and the corresponding edge of the side wall are seamed or crimped together in well known manner to make tight joints 15 at 73 and 74. Adjacent the joint 73 cap 71 has an annular flat portion 75 surrounding an outwardly bulged middle portion having an opening through the center thereof with an interiorly screw-threaded reinforcing sleeve or bushing 16 20 secured in said opening. Cap 72 is similarly formed with an annular flat portion 77 surrounding an outwardly bulged middle portion having through the center thereof an interiorly screw-threaded reinforcing sleeve or bushing 18. The 25 container 70 is shown in Fig. 5 as being mounted on dash 79 of an automobile by means of two metal straps 80, such as shown in Fig. 6, with small bolts 81 passing through the dash and a 30 hole 82 in each end of the straps. 35

83 is a portion of the wall of a crank casing having therethrough a screw-threaded outlet opening engaged by one end of a nipple 84 (similar to nipple 31 of Fig. 1) the other end of which is threaded into the lower branch of a T-coupling 85. A pipe 86 connected by a pipe joint 87 to the upper branch of coupling 85 leads to an oil gauge 87' suitably located for observation. A pipe 88 (known as the "feed line" to the oil clarifier) is connected at its lower end to the side branch of T-coupling 85 by a suitable pipe joint 89 having therethrough a small passage 90 for limiting the flow of oil, preferably a No. 50 drill hole. At its upper end pipe 88 is connected to the bottom of the casing by means of a suitable pipe joint 91, the screw-threaded upper end of which engages the screw-threaded opening through bushing 18. A pipe 92 (known as the "return line") is connected at its upper end to the interior of the casing by means of a pipe joint 93 having a 45 screw threaded end which engages through bushing 76 of the end cap 71. At its lower end pipe 92 communicates with the interior of the crank case through a pipe joint 94 the lower end of which is screw threaded into an opening through 50 a part 83' of the wall of said crank case. 55

The inside surface of the cylindrical wall of the container is covered with a suitable adhesive 95, such as silicate of soda. A circular screen 96 fits closely within the casing at the bottom 60 thereof, rests against the shoulder formed by annular flat portion 77 of cap 72, and provides an open space 97 between its bottom surface and the cap 72. A body of fibrous material 98 bears upon screen 96 and fills the casing transversely 65 and vertically to a height somewhat less than one-half of the height of the interior of the casing. At its periphery the body of material 98 engages the adhesive 95 and is attached by the latter to the vertical wall of the casing. A body 70 75

of fuller's earth 99 rests against the fibrous material 98 and fills the casing transversely and vertically above material 98 to near the top of the casing. As shown, the depth of the fuller's 5 earth 99 is about the same as that of the fibrous material 98. At the periphery of the body of fuller's earth the particles thereof engage the coating of silicate of soda 95 and are attached thereby to the wall of the casing. Above the fuller's earth there is a relatively shallow layer or 10 pad of fibrous material 100, such as ordinary cotton waste, which pad is also attached at its periphery to the wall of the casing by engagement with the adhesive coating 95. Immediately above 15 the pad of waste 100 there is a circular wire screen 101 and above the latter a circular perforated plate 102 which bears against the annular shoulder formed by the flat portion 75 of cap 71. Between the plate 102 and the cap 71 there is an 20 open space 103. The screens 96 and 101 may be ordinary steel fly screening of a mesh, say about $\frac{1}{8}$ inch, suitable for keeping particles of waste from the pad 100 from passing out with the filtered oil and for supporting the body 98 of fibrous 25 filtering material.

The circulation of oil from the engine through the filter in Fig. 5 is very much the same as hereinbefore described in reference to the filter of Fig. 1. Oil is forced under pressure from the crank 30 case at 83 through the feed line 88 into the space 97 at the bottom of the filter; thence through screen 96, fibrous filtering material 98, fuller's earth 99, screen 101 and perforated plate 102 into space 103 at the top of the filter; and thence 35 through the pipe or return line 92 back to the crank case at 83'. Upward movement imparted to the fibrous material 98 by the oil pressure acts upon the fuller's earth above in the same manner as explained in connection with Fig. 1. The feed 40 line 88 of Fig. 5 may be provided with a check valve similar to that shown in Fig. 7 and for the same purpose.

In describing the action and cooperation of the fibrous material and the fuller's earth in removing 45 impurities from the oil circulated therethrough, it is appropriate to begin by referring to the character of those impurities. It is well known that oil used in lubricating systems of internal combustion engines, especially on automobiles, tends to become contaminated with various 50 impurities with consequent diminution of the lubricating property and value of the oil. The variety of such impurities, the sources from which they become present in the oil, and their 55 injurious effects upon the oil, are generally indicated by the following quotations from accepted authorities, to wit:

"Chemical Refining of Petroleum", published 1933, by Vladimir A. Kalichevsky—Research Laboratory, Socony-Vacuum Corp., and Bert Allen Stagner, formerly Supervisor of Chemical Research, Union Oil Company, on page 335 states:

"When used in an automobile engine, a lubricating oil not only becomes contaminated with 60 the higher boiling constituents of gasoline and coke-like products from the combustion chambers, dust from roads, and worn fragments from the bearings, but some of the oil itself slowly undergoes partial oxidation from contact with the 65 air and eventually forms deleterious products in sufficient quantity to render further use of the oil unsafe. In the oxidation are found organic acids, which attack the metal parts of the motor and produce metal soaps insoluble in oil, and other 70 oxidation products which undergo transforma- 75

tion by polymerization, condensation, etc., into semi-solid gum-like material, for the most part insoluble in the oil. The material separating from the oil is known as 'sludge'."

"Automobile Engine Lubrication Oils" by Bureau of Standards (March 22, 1934) on page 3 states:

"Due to their instability under service conditions, all motor oils undergo certain changes during use. The changes occurring are: (1) cracking, or decomposition of the oil into lighter compounds and a carbonaceous residue, and (2) oxidation, or combination with oxygen to form organic acids and products of an asphaltic nature, called asphaltines."

See also the decision of the Court of Appeals for the Sixth Circuit in the case of Motor Improvements Inc. et al. v. General Motors Corporation et al., 49 Fed. (2d) 543, 544.

For present convenience, the impurities may be divided into two groups, first, carbon, dirt, water, etc., which are removable mainly by mechanical filtration; and, second, acids, resins, asphaltic matter, etc., which are removable by adsorption filtration or refining, but not by mechanical filtration. I have practically demonstrated that fuller's earth alone, when used in accordance with my previously mentioned patent, will effectively remove all of these impurities, the carbon, dirt, water, etc., by mechanical filtration, and the acids, resins and asphaltic matter by adsorption filtration or refining. But it has been found that to give such a filter the desired life or mileage capacity, before replacing the fuller's earth, requires the use of a considerable volume of said earth such as to result in a relatively large filter, which for that reason alone may be inconvenient and objectionable for use on pleasure automobiles in particular. I have found that fibrous material such as waste, while effective 40 (and even more so than a like volume of fuller's earth) for removing the carbon, dirt, water, etc., by mechanical filtration, is not effective for removing acids, resins and asphaltic matter.

By using, according to the present invention, 45 both kinds of material, waste and fuller's earth or their equivalents, I thereby especially utilize those properties of each which render it more effective than the other in removing certain of the impurities; and furthermore, by removing certain of the impurities by one material I make it possible for the other material to act more effectively and efficiently in removing the other impurities. More specifically, upon the passage 50 of the oil through the fibrous material (64 in Fig. 1 and 98 in Fig. 5), the latter removes from the oil, principally by mechanical filtration, carbon, dirt, water, etc. The extraction of those impurities by the fibrous material has the highly 55 important additional advantage of preventing said impurities from being carried into the fuller's earth where they would lodge on the surfaces of the particles and in the interstices between said particles, thereby interfering with or obstructing the adsorption functioning of the fuller's 60 earth and materially shortening its useful life in removing from the oil the acids, resins and asphaltic matter. From the fibrous material the partly purified oil passes through the fuller's 65 earth (65 in Fig. 1 and 99 in Fig. 5), which, as 70 stated above, acts by adsorption to remove acids, resins and asphaltic matter.

Thus, by repeated circulation through the filtering means of this invention, a fresh charge of pure oil in the lubricating system will be main- 75

tained in its original condition during the useful life of the filtering materials; or a charge of oil previously contaminated with impurities will be speedily restored to its original pure condition 5 and thereafter maintained in that condition during the useful life of the filtering materials. In either case, the useful life of the filtering means of this invention will, it is believed, exceed by many thousand miles the supposed useful life of 10 oil filters of the types heretofore most commonly used on automobiles.

The method and means of this invention afford other important and mostly self-evident advantages in addition to those hereinbefore indicated. For example, a filter is provided which is believed to be of greater efficiency in removing 15 impurities, including acids, resinous and asphaltic matter, than any filter heretofore produced. It may be made of small size or dimensions while at the same time being capable of 20 prolonged efficient operation. It may be furnished to users at relatively low cost and its filtering materials replaced at small expense. Removal of some of the impurities by the fibrous 25 material enables the fuller's earth to act with greater efficiency in removing other impurities. The effective life of the fuller's earth being thus greatly prolonged, a smaller mass or body thereof may be used. The combined volume of both 30 fibrous material and fuller's earth may be considerably less for a given maximum mileage of use than when fuller's earth alone is used.

While the best results are believed to be obtainable by the use of separate bodies of fibrous 35 material and fuller's earth and by circulating the oil through said materials in that order, nevertheless good results are believed to be obtainable by reversing that order. Furthermore, equivalents of said materials may of course be employed. For example, adsorbent materials such 40 as alumina, or carbon, may be used in place of fuller's earth and would, it is believed, give good results. But fuller's earth is preferred because it is the least expensive while at the same time 45 highly efficient.

My aforesaid Patent 1,860,229 shows and describes (p. 2, lines 7-12) "small quantities or layers 22 and 23 of wool, gravel or other suitable oil spreading material", placed in the top and bottom portions of the casing above and below 50 the body of fuller's earth, and states that either one or both of these "spreading layers" may be omitted. The oil passes through and is spread by said top layer 22 before it (the oil) enters the 55 fuller's earth. Upon leaving the fuller's earth, the oil passes through the bottom layer 23 which the patent also states (p. 2, lines 66-69) may be of "waste, wool or the like". It will be apparent that neither of said shallow bodies of material 60 22 and 23, whether of wool, waste, gravel or other "suitable oil spreading material", would act as a filtering medium or was intended for that

purpose; and that any impurities extracted by said layers 22 and 23 upon passage of the oil therethrough would be of negligible quantity. According to the present invention the fibrous filtering material (64 of Fig. 1 and 98 of Fig. 5) 5 must be of sufficient mass and depth to remove a substantial amount of impurities from impure oil circulated therethrough.

What is claimed is:—

1. The combination with the pressure lubricating system of an internal combustion engine, of filtering means comprising a column, of substantial length, of compressed fibrous filtering material, an adjacent column, likewise of substantial length, of mineral adsorbent particles, 15 of a particle size lying between 8 and 60 mesh, less tightly compressed than is said column of fibrous filtering material, a compressible packing layer adjacent that end of the column of mineral adsorbent particles which is remote from the 20 compressed fibrous material column, means for holding the said columns and compressible packing layer under compression, and means for continuously passing oil under pressure from said system during operation of said engine through 25 said column of fibrous material into and through said column of adsorbent material and back to the system.

2. Oil filtering system in the pressure lubricating system of an internal combustion engine, comprising, in combination, a container, inlet and outlet passages in said container, each communicating with said pressure system, a removable tight covering means for said container and spaced from said inlet and outlet passages, 30 and a filtering cartridge replaceable through said covering means and positioned within said container functionally between said inlet and outlet passages whereby oil introduced under pressure through said inlet passage normally passes through said cartridge in moving to said outlet passage, said replaceable filtering cartridge comprising a columnar casing provided with foraminous end closures and filled with filtering material 35 under compression, said filtering material divided into two adjacent and communicating masses one of which is a column, of substantial length, of fuller's earth particles having diameters lying between 8 and 60 mesh and the other of which is a column, of substantially equal length, of relatively compact spirally wound layers of fibrous filtering material the strata of whose layers are 40 substantially parallel with the longitudinal axis of the cartridge casing, the outermost layer of fibrous material being adhesively fixed to the 45 contiguous inner surface of said cartridge casing while permitting the more centrally disposed layers to move longitudinally of the cartridge casing toward the mass of fuller's earth particles 50 under the influence of pressure applied against 55 their outer ends.

SOUTHWICK W. BRIGGS.
